UNITED STATES PATENT OFFICE

HAROLD CARLE, OF BUFFALO, NEW YORK, ASSIGNOR TO F. N. BURT COMPANY LIMITED,
OF TORONTO, ONTARIO, CANADA, A CORPORATION OF ONTARIO, CANADA

MACHINE FOR MAKING PAPER BOXES

Original application filed April 27, 1923, Serial No. 635,078. Divided and this application filed July 19, 1928, Serial No. 293,899. Renewed August 31, 1932.

This invention relates to mechanism for feeding and positioning box elements and with respect to its more specific features to blank feeding and positioning mechanism employed in machines for automatically making paper boxes and parts of such boxes.

One object of the invention is the provision of a simple mechanism adapted to deliver blanks one by one from a magazine and place the blanks accurately in another position; as for instance, on a mandrel, or former, of an automatic box making machine.

Another object of the invention is the provision of a blank magazine and blank feeding and blank placing devices of simple and practical construction, capable of readily cooperating with other instrumentalities; as for instance, other mechanism of an automatic box making machine.

Other objects of the invention will in part be obvious and will in part appear hereinafter.

This invention accordingly comprises the features of construction, combinations of elements, and arrangement of parts, which will be exemplified in the construction hereinafter set forth and the scope of the application of which will be indicated in the claims.

For a fuller understanding of the nature and objects of the invention, reference should be had to the following detailed description taken in connection with the accompanying drawings, in which:

Fig. 1 is a side elevation showing the blank magazine, the blank feeding mechanism and associated parts;

Fig. 2 is a plan view of the blank actuating devices illustrated in Fig. 1;

Figs. 3 and 4 illustrate details of the feeder actuating mechanism;

Fig. 5 illustrates a detail of the blank magazine;

Fig. 6 illustrates a detail of the placer actuating devices;

Fig. 7 illustrates a portion of the frame of the machine with certain of the operating instrumentalities mounted thereon;

Fig. 8 is an elevation of a portion of the machine and showing a cam shaft in related position; and

Fig. 9 is a plan of a portion of the upper table of the machine with certain operating mechanism mounted thereon.

Referring now more specifically to the drawings, it is to be noted, that this application is a division of application Serial No. 635,078, filed April 27, 1923 to which reference is made for full disclosure of the automatic box machine of which the herein described mechanism is a part.

As in the prior application, the frame of the machine includes an upper table 1 having usual supporting legs 2. On a table 3, which is immediately below the table 1, there is mounted an electric motor 4 which drives 55 the cam shaft 5 through the gears 6, 7, 8 and 9, when the clutch 10 actuated by the clutch shifter rod 11, is thrown in. On the cam shaft 5 is a cam 12 which controls operation of the blank placer 13, hereinafter more 60 specifically described. Supported in brackets 14 depending from table 1 is the cam shaft 15 having a cam 16 which controls operation of the blank feeder, hereinafter more specifically described. Cam shaft 15 is driven from 65 shaft 5 through sprocket wheels 17 and 18 and the operating connecting chain 19.

As in the prior application above mentioned, a plurality of turret arms intermittently rotate in a horizontal plane above the table 1. On the end of each of the turret arms is a rectangular former or mandrel. These mandrels successively come to rest at a station where body blanks are placed thereon by the placer 13. In Fig. 1, one such 70 mandrel is indicated at 20, at its position of rest, ready to receive the body blank from placer 13.

In order that the blanks may be retained upon the mandrel 20 when the placer 13 recedes, the blank may be held on the mandrel by suction. For this purpose, suitable pneumatic gripper openings and grooves are provided in the blank receiving face of the mandrel 20 and controlled conduits extend from the pneumatic gripper openings to a pump or exhaust apparatus 21. The pneumatic gripping devices and the conduits are fully described in the prior application and reference is made thereto for full description.

In the present embodiment of the invention, the blanks to be fed and controlled are rectangular corner cut blanks, one of such blanks being indicated in dotted lines at 22 in Fig. 2 of the drawings. These blanks may be made of cardboard or pasteboard and have considerable stiffness so as to form the body blank of a paper box which is made by the automatic machine described in the prior application. These body blanks are relatively thick as compared with the cover paper which may be employed to give the finished boxes an ornamental appearance.

The blank magazine, includes a plate 23 which constitutes the base of the magazine. Side walls of the magazine are indicated at 24. The side walls are connected to the base plate for adjustment toward and from each other by means of screws 25, which pass through slots in angle plates 26 to which the side walls are secured, into engagement with the plate 23. A pair of blank supporting rails 27 is arranged at each side of the plate 23 on the top thereof, and each pair is connected to the plate for adjustment toward and from the other pair by screws 28 passing through slots in outwardly extending feet 29 on the outermost rail of the pair.

The blank feeder includes two pusher bars 30 which are mounted to slide on and move between the members of each pair of rails, and the bars 30 are connected at the end remote from the mandrel 20 by means of a crosshead 31. The crosshead is connected to a slide 32 mounted to move in a guideway 33 on the underside of the plate 23, and at the center thereof. The inner members of the pairs of rails are rabbeted on their outer faces and at their upper edges, to receive the bars 30, and the inner wall of the rabbet has a longitudinally extending rib 34 engaging a similarly shaped groove in the adjacent bar, thereby to guide the bar. The corner-cut body blanks 22 which are cut to shape, each comprise a rectangular body and side and end flaps, adapted to be folded on mandrel 20, to provide an open rectangular box or tray, and these blanks rest in a pile upon the rails 27, and they are held in position in the magazine, by a gauge bar 35 on the table 23 and by spring plates 36 on the side walls.

The gauge bar 35 is adjustably connected with the table, by a screw and slot connection indicated at 37 and the resilient plates 36 are adjusted toward and from each other, by means of set screws 38 threaded through the side walls 24 and provided with locking nuts for holding them in adjusted position. The spring plates 36 are adapted to center the blanks in the magazine and are connected to the side walls at their upper edges, their lower edges being outside the rails 27, and being free, so that by turning

the set screws 38, the spring plate 36 may be flexed and the alignment of the blanks with respect to the transferring mechanism, to be later described, may be assured. The end flaps of the blanks rest on the rails, and the spring plates 36 engage the free edges of the said flaps, thus acting to guide the blanks in the magazine. The gauge bar 35 engages back of the pile of superposed blanks, as shown in Figure 2. The pusher bars 30 extend above the rails 27, a distance corresponding to the thickness of a blank, so that when the pusher bars are moved toward the mandrel 20, they will engage the lowermost blank in the magazine and push 80 and deliver it out from beneath the pile.

A pair of blank retaining fingers 40 are arranged at the front of the magazine, for preventing the passage of more than a single blank. As shown in Figures 1 and 5, the retaining fingers are adjustably connected to angle plates 41 supported by the side walls. Each finger is adjustably connected with the adjacent angle plate, by a screw and slot connection 42, and the lower ends thereof are spaced above the rails, just far enough to permit the passage of one blank. The lower outer corner of the fingers are beveled, and by loosening the screws, the fingers may be adjusted vertically in accordance with the thickness of the blank.

The slide 32 is operated by a rock arm 43 pivoted at 44 to the table 1 and having one arm connected by a link 45 with the slide. The other arm of the rock shaft is connected by a link 46 (Figure 3) with operating mechanism to be later described.

The blanks are fed from the magazine onto a blank placer which is reciprocally movable between the position in which it receives blanks from the magazine and blank placing position, in which latter position the blank is placed on the mandrel. The placer includes a swinging table or placer plate 13. This plate is secured to one of the arms 47 of a rock shaft 48 journaled in bearing brackets 49 on the table 1, and it is normally spring held in lowered, horizontal, blank receiving position, below the upper edges of rails 27, by means of a coil spring 50 arranged between another arm 51 on the rock shaft, and a stop on the table. The arm 51 is connected by means of an adjustable link 52 with operating mechanism to be later described. At regular intervals, the placer plate is swung upwardly into vertical position, as shown by dotted line position of Figure 1, by the operating mechanism connected with the link 52, to present a blank against the outer face of the mandrel 20 which at this time is in alignment with the magazine and swinging placer. The swinging plate has stops or gauges 53 connected therewith for longitudinal adjustment by screw and slot connections 54, and each gauge 53 has a portion for engaging 130

the end of the end flap of the blank, and a portion for engaging the forward edge of the blank, the two stops being joined together, and also adjustable as one by the connections 54.

5 When the swinging placer presents a blank to the mandrel, the pneumatic gripper grooves and openings of the mandrel are connected with the exhausting mechanism, as by means described in the prior application, and the body of the blank is held against the mandrel by suction, the flaps of the blank projecting beyond the sides and ends of the mandrel.

10 The shaft 5 before mentioned is journaled in bearing brackets 55 on the lower table, and it is driven from the motor 4 mounted on the table 3. The shaft of the motor has a wide pinion 6, which meshes with a pinion 56 on the shaft of exhauster 21, for controlling the suction of the mandrels 20, and with the gear wheel 7 at the opposite side from the pinion 56. The gear wheel 7 is journaled on the frame, and carries the pinion 8 which meshes 15 with the gear wheel 9 on the shaft 5. The gear wheel 9 is loosely mounted on the shaft 5 and clutch mechanism indicated at 10 is provided for connecting the gear wheel with the shaft. The shaft 15 carries a cam 58 which operates the blank feeder. The shaft 15 at the cam 58 is embraced by a slotted slide or follower 59, having a friction roller 60 engaging the cam edge. The link 46 before mentioned connects the follower 20 with one of the arms of the rock shaft 44 before mentioned, and a spring 61 arranged 25 between the rock shaft and the table, acts to hold the friction roller 60 in engagement 30 with the cam.

35 The rock shaft 48 is operated to swing the body blank, fed onto the placer table 13, into engagement with the mandrel 20 by means of the cam 12 secured on the shaft 5 (Figure 40 6). A lever 62 is pivoted to a support 63 adjacent the cam and is provided intermediate its ends with a friction roller 64 engaging the edge of the cam. The link 52 has a 45 slideable and universal joint connection with the lever 62.

40 In operation, a pile of the body blanks will rest upon the rails 27, and be retained in superposed relation by the upstanding angle bars 41 and the gauges 35. The left hand ends of the feeder bars 30 will be immediately 45 behind the edge of the lowermost blank 22, at the start of the blank feeding operation. Advance of the feeder bars 30 will deliver the lowermost blank from the magazine on to the placer table 13, the position of the blank 50 on the table 13 being determined by the gauges 53 which will lie against the extreme ends of the flaps and also against the front edges of the end flaps. The remaining blanks 55 of the pile would be supported by the under- 55 lying feeder bars 30. The placer table will

then swing upwardly and place the body blank against the end of the mandrel 20, the exhaust apparatus being energized at this time to cause the body blank to be gripped to the face of the mandrel 20. The gauges 53 70 are sufficiently far apart to lap on to the sides of the mandrel so as not to interfere with the placing operation. Upon recession of the feeder bars 30, the pile of blanks will drop on to the rails 27 and the next lowermost 75 blank will be delivered by the next feed movement of the bars 30. Meantime, the placer table 13 will have been lowered to horizontal position for reception of this next blank. After the mandrel 20 has received a blank, it 80 will be rotated away from blank receiving position for further operations upon the blank held thereby. But another mandrel 20 will be moved into position to receive the succeeding body blank elevated by the placer 85 table 13.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a machine of the character described, in combination, a magazine for containing a pile of superposed blanks, a blank feeder for delivering blanks from said magazine, and a blank placer reciprocally movable between 100 blank placing position and a position to receive blanks delivered by said feeder, and resilient blank guides adjustable to center the bottom blanks in the magazine.

2. In a machine of the character described, in combination, a magazine for containing a pile of superposed blanks, a blank feeder for delivering blanks from said magazine, and a blank placer reciprocally movable between 105 blank placing position and a position to receive blanks delivered by said feeder, said magazine including an adjustably mounted side wall, a blank adjusting, spring plate supported by said wall inside the magazine, and means to flex said plate.

3. In a machine of the character described, in combination, a magazine for containing a pile of superposed blanks, a blank feeder for delivering blanks from said magazine, a blank placer reciprocally movable between blank placing position and a position to receive blanks delivered by said feeder, said magazine including a pair of blank supporting rails, blank adjusting guides outside said rails, and blank retaining fingers, one 115 above each of said rails.

4. In a machine of the character described, in combination, a magazine for containing a pile of superposed blanks, a blank feeder for delivering blanks from said magazine, a blank 120

placer reciprocally movable between blank placing position and a position to receive blanks delivered by said feeder, a pair of blank supporting rails, said feeder including 5 a pair of blank pushers sliding on said rails and extending above said rails.

5. In a machine of the character described, in combination, a magazine for containing a pile of superposed blanks, a blank feeder for 10 delivering blanks from said magazine, a blank placer reciprocally movable between blank placing position and a position to receive blanks delivered by said feeder, a pair of blank supporting rails, said feeder including 15 a pair of blank pusher bars sliding on and having rabbeted engagement with said rails.

6. In a machine of the character described, in combination, a magazine for containing a pile of superposed blanks, a blank feeder for 20 delivering blanks from said magazine, a blank placer reciprocally movable between blank placing position and a position to receive blanks delivered by said feeder, a base plate, a pair of blank supporting rails mounted 25 on the top of said base plate, said feeder including a pair of connected blank pusher rods sliding on said rails, and a reciprocally movable pusher slide mounted on the bottom of said base plate.

7. In a machine of the character described, in combination, a magazine for containing a pile of superposed blanks, a blank feeder for 30 delivering blanks from said magazine, a pair of blank supporting rails, and a blank placer reciprocally movable between blank placing position and a position to receive blanks delivered by said feeder, said placer having swinging movement between blank placing and blank receiving positions, said 35 feeder including pusher bars sliding on, and extending above, said rails.

8. In a machine of the character described, in combination, a magazine for containing a pile of superposed blanks, a blank feeder for 40 delivering blanks from said magazine, a blank placer reciprocally movable between blank placing position and a position to re-

ceive blanks delivered by said feeder, and a pair of blank supporting rails below the upper edges of which said placer is disposed when in blank receiving position, said feeder including pusher bars having rabbeted engagement with said rails. 70

9. In a machine of the character described, in combination, a magazine for containing a pile of superposed blanks, a horizontally reciprocal blank feeder for delivering blanks 75 from said magazine, a pair of rails on which the blanks slide on delivery from the magazine, a blank placer plate having swinging movement from vertical, blank placing position to horizontal blank receiving position beneath the upper edges of said rails, and blank gauges on said placer plate. 80

10. In a machine of the character described, in combination, a magazine for containing a pile of superposed blanks, a horizontally reciprocal blank feeder for delivering blanks 85 from said magazine, a pair of rails on which the blanks slide on delivery from the magazine, a blank placer plate having swinging movement from vertical, blank placing position to horizontal blank receiving position beneath the upper edges of said rails, and blank gauges on said placer plate, said gauges including longitudinally and laterally gauging members joined together and longitudinally adjustable on said placer plate. 90

11. In a machine of the character described, in combination, a magazine for containing a pile of superposed blanks and including a blank adjusting, spring plate supported inside the magazine, means adapted to flex said 100 spring plate, a pair of blank supporting rails, a blank feeder including pusher bars sliding on and extending above said rails and having rabbeted engagement with said rails, and a blank placer plate having swinging movement from blank placing position to blank receiving position beneath the upper edges of said rails. 105

In testimony whereof I affix my signature. 110

HAROLD CARLE.
